UNITED STATES PATENT OFFICE.

EDMUND E. BROWN, OF BLOOMINGTON, ILLINOIS, ASSIGNOR, BY MESNE ASSIGNMENTS,
TO SOUTHERN IRON AND STEEL COMPANY, A CORPORATION OF NEW JERSEY.

WIRE-FENCE MACHINE.

1,025,858.

Specification of Letters Patent.

Patented May 7, 1912.

Application filed June 28, 1904. Serial No. 214,566.

To all whom it may concern:

Be it known that I, EDMUND E. BROWN, citizen of the United States, residing at Bloomington, in the county of McLean and 5 State of Illinois, have invented certain new and useful Improvements in Wire-Fence Machines; and I do hereby declare that the following is a full, clear, and exact description of the invention, which will enable 10 others skilled in the art to which it appertains to make and use the same.

This invention has reference to a machine for the manufacture of wire fence and is particularly adapted for making a wire 15 fence having a square mesh, and composed of longitudinal or line wires and a series of stay wires or pickets. The machine here shown being adapted to produce a fence having a graduated mesh, but this is not 20 material as it may be made to produce a uniform mesh.

The stay wires or pickets are short sectional stays corresponding to the number of 25 spaces between the longitudinal or line wires and such spaces are spanned by the sections of stays and the adjacent ends of each section coinciding with the same longitudinal wire are locked and coiled upon such longitudinal wires, the sections of stay 30 when joined with adjacent longitudinal wires having the appearance of a continuous stay from selvage wire to selvage wire.

The invention has for its object a series of 35 vibratory hoppers or stay receptacles and a series of revolvably carried disks or stay carriers which are adapted to receive successively short sections of stay and feed them to means for intertwisting or coiling them around the longitudinal wires.

40 The invention has for its further object a series of vibratory hoppers disposed in two rows, alternate hoppers being in the opposite row, revolvably carried disks for receiving stay sections from said hoppers and 45 revolvably carried knotter plates adapted to receive the ends of the stay sections for coiling them around the longitudinal or strand wires.

A further object of the invention is a series 50 of vibratory hoppers; a series of feeding disks co-acting with the hoppers and adapted to receive short sections of stays and deposit them upon means where the opposite ends of such stay sections are bent at 55 right angles to their length; and revolvably

supported coiling or knotter plates for receiving the bent portions of the stay sections and coiling or directing the same around the longitudinal wires.

The invention has for its further object a 60 series of receptacles for carrying short sections of stays; a series of revolvable feeders; means for depositing short sections of stays from the receptacles upon the feeders, the feeders adapted to retain the stay sections 65 momentarily in a stationary position and during such period of rest, the opposite ends of the stay sections are bent at right angles to their length; means for coiling the bent 70 portions of the stay sections around adjacent longitudinal or strand wires and means for delivering the short sections of stays from the feeders to the coiling devices.

The invention has for its further object 75 a pair of knotter-plates co-acting with each other and revolvble in opposite directions, and carrying means for receiving portions of the opposite ends of stay wires.

The invention has for its further object a 80 pair of knotter plates co-acting with each other, wire receiving portions upon the matching faces of the said plates and means upon each plate for depositing the ends of opposite stay sections in the wire receiving 85 portions of the opposite plates.

The invention has for its further object a 90 pair of knotter-plates co-acting with each other, revolvably supported and one of said plates supported by a frame adapted to be raised and lowered and means upon the matching faces of the plates for receiving portions of stay wires and directing them in opposite directions around a coinciding strand wire.

The invention has for its further object, 95 vibratory stay receptacles and rotary feeding disks coöperating therewith, having notched peripheries for receiving the stays from the receptacles; reciprocally disposed stay receiving devices and means coöperating therewith for bending the opposite end of the stays at right angles to their lengths; reciprocally disposed members for engaging the stays and lowering the same upon the longitudinal strand wires with which the bent portions are inter-coiled; revolvably supported knotter plates having acting faces which are adapted to be brought adjacent to each other for receiving and coiling the 100 ends of the stays around the strand wires; 105 110

means for shifting the knotter plates toward and from each other; means for raising and lowering one set of knotter plates and crimping devices for the strand wires located intermediate the wrapping devices and the knotters.

The invention has for its further object, details of construction to be hereinafter more particularly specified in the specification and illustrated in the accompanying drawings forming a part of this application.

Figure 1 represents a general outline view of one side of the machine; Fig. 2 is a plan in outline of the complete machine. Fig. 3 is a general view in outline of the side of the machine opposite to that shown in Fig. 1. Fig. 4 is a view in outline of the machine and the operative parts thereof, looking at the machine the same as in Fig. 3 but the forward frame part of the machine being removed to show the relation of the parts. Figs. 5, 6 and 7 represent a front and side elevation and a longitudinal cross section of tension devices forming a part of the feed 25 for the strand wires. Figs. 8, 9 and 10 represent details of certain registering devices and an alarm, employed for the purpose of registering the number of rods of wire passing into the machine. Fig. 11 is a vertical 30 and longitudinal sectional view of mechanism for feeding and forming the stay sections to the line wires; the plane of the section is approximately on the line $a-a$ of Fig. 12. Fig. 12 is a transverse sectional view of the stay section feeding and forming devices and is taken on the line $b-b$ of Fig. 11, looking toward the head of the machine. Fig. 13 is a sectional plan of the mechanism which performs the operation 35 of bending at right angles, the opposite ends of the stay sections. Fig. 14 is a plan view of certain collecting fingers and compression shoes which form a part of the stay section feeding devices. Figs. 15, 16 and 17 represent two opposite side elevations and an edge view of certain intermittent gearing for driving a part of the feeding devices. Fig. 18 is a detail in perspective of a portion 40 of a delivering fork, several of which carry the stay sections from the feeding devices to the strand wires and knotter mechanism. Fig. 19 is a plan view of the twisting and knotter mechanism which secures the stay sections to the strand wires. Fig. 20 is a 45 sectional elevation taken approximately on the line $c-c$ of Fig. 19. Figs. 21, 22 and 23 show edge views of a pair of knotter plates; the several views being shown to show the relation of the knotter plates previous to receiving the ends of the stay sections and subsequent movements thereof. Fig. 24 is a face view of a twister and a knotter plate. Figs. 25, 26 and 27 represent 50 a pair of knotter plates showing the different stages of their operation; one of the

plates being removed a short distance from the other in each of the views to afford a better view of the operation. Fig. 28 is an elevation showing a part of the crimping mechanism for the strand wires, looking toward the head end of the machine. Fig. 29 is a sectional elevation of the crimping mechanism shown in Fig. 28. Fig. 30 is a plan view partially in section of the wire fence reeling or wrapping mechanism. Fig. 31 is an elevation in detail of ratchet mechanism coöperating with the reeling device, and Fig. 32 is a side elevation of the reeling device and the mechanism for operating the reel. Fig. 33 shows a style of fence made 55 on this machine.

In the drawings, like numerals of reference indicate corresponding parts throughout the figures.

The machine consists of a bed composed 60 of the side frames which support the general working parts of the machine, including the wire feeding and wrapping devices. At a suitable point in the frame, 1, there is journaled transversely, the power shaft 2 carrying on one end, a freely revolving power pulley 3 around which travels a belt 4, adapted to be driven from any convenient source of power, not shown. The pulley 3, is adapted to be made secure to its shaft 2 through the clutch 5 operated by a hand lever 6, situated on the opposite side of the machine and attached to the vertical shaft 7, journaled in suitable bearings and its lower end connected with the crank 8 and the rod 9, the latter having connection with the clutch previously referred to. These devices are clearly seen in Figs. 1, 2 and 3.

10 denotes a main driving shaft and owing to its reduced speed and the amount of pressure required to drive it, for reasons in practice, is operatively connected with the power shaft 2 through compound gearing, of which 11 is a pinion secured to the power shaft and intermeshes with a gear wheel 12 keyed to an intermediate shaft 13, which shaft is properly journaled in bearings supported on the bed frame and also carries the pinion 14 which intermeshes with a gear wheel 15 on the main driving shaft 10 for the purpose of transmitting power thereto. The shaft 10 is journaled in suitable bearings on the bed frame and carries cams, cranks, a segment gear, and a main sprocket gear, the location and uses of which 110 will be hereinafter fully described.

16 denotes a secondary driving shaft suitably positioned in the bed frame and receives its power from the main driving shaft 10 through a sprocket wheel 17 on the shaft 125 15 connected by a sprocket chain 18 with a sprocket gear 19 on the shaft 16. The sprockets 17 and 19 are of equal size, therefore the shafts 10 and 16 rotate in unison. The shaft 16 like the shaft 10 also carries 130

a number of cams and a segment gear, the purposes and location of which will be further described. On the opposite end of the shaft 16 is carried a sprocket pinion 20 which transmits motion to a shaft 21 for operating suitable feeding devices, through a pinion 22 engaging a sprocket pinion 23 carrier on one end of the shaft 21. Upon the opposite end of the shaft 21 is carried a sprocket pinion 24 which transmits motion to a short shaft or stud 25 by means of a sprocket chain 26 traveling around the pinion 24 and a pinion 27 carried on the stud; and by means of the stud and suitable devices carried thereby, motion is imparted to a transverse shaft 28, the same adapted to actuate suitable revoluble disks which form a part of the feed to be herein-after described.

Having described the power shaft together with the mode of driving it, the main driving shaft and secondary shafts which control the operation of the stay section feed devices, I will now describe the manner of feeding in the strand wires and follow up such description with the operation of the feeding devices and the manner of coiling the ends of the stay sections around the strands, and the further process of crimping the strand wires and reeling the completed fabric.

At the forward end of the machine, is a series of independently arranged tension devices for holding each one of the strand 35 and selvage wires; such tension devices consisting of two grooved rollers 29 and 30 between which the strand wires are drawn. The roller is revolubly carried in a stationary frame 31 and the roller 29 is revolubly carried in a frame part 32 hinged at 33 to an extension of the frame 31 which is for the purpose of adjusting the roller 29 and to facilitate in its removal for the insertion of a strand wire between the two rollers.

To cause the roller 30 to revolve with the movement of the strand wire and to prevent any slipping, the roller 29 is compressed against or caused to impinge the roller 29 by means of a spring 34 which is carried around a threaded stem 35, one end of which is attached to the free end of the frame part 32 and the opposite end passes through a U frame or yoke 36 which is detachably connected at its lower portions 55 with the frame 31; and 37 is a thumb nut engaging the outer end of the stem 35, which is kept loose, but which when tightened against the U frame or yoke 36, assumes all the pressure of the spring and affords an easy removal of the pin which holds the U frame or yoke so that the swinging frame 32 carrying the roller 29 may be swung out of position as shown in Fig. 6. The object of such a tension device, is to offer resistance 65 to the passage of the wires through the ma-

chine, and for this purpose, a brake is applied to the roller 30 and consists of a brake shoe 38 which is held against the roller 30 by means of a spring 39 seated in the frame 31. The brake shoe is retained in its relative position with the roller in the frame by means of top and bottom flanges 40 which project slightly over the frame 31, as shown in the Fig. 6. These tension devices are all mounted in a row on a sill 42 supported by the main frame and are positioned to suit the space between the strand wires. Only one of the tension devices has been described, but as they are all similar, the description of one, will it is thought suffice for all. Coöperating with the tension and feeding devices is an equalizing drum 43 which is secured to a transverse shaft 44 journaled in the frame 1, and around which each strand and selvage travels once, serving to equalize the feeding of the strand wires through the machine. The shaft and drum are operated only by the action of the drawing in of the strand wires, which is accomplished by means of the reeling devices which wind up the completed fabric 90 to be further described.

To ascertain the length of the strand wires fed to the machine and consequently the length of the finishing product, a registering device is attached to and is operated by the shaft 44 to which the drum 43 is attached. This registering device is represented by the numerals 8, 9 and 10 and consists of a pinion 45 attached to one end of the shaft 44 and meshing with a gear 46 on a short shaft 47 journaled in a bracket 49 supported by the main frame 1. The proportionate sizes of the pinion 45 and the gear 46 are such that the gear 46 makes one revolution while the strand wires advance one rod. The outer face of the gear 46 is provided with a scale and graduated to represent feet, being read with the aid of a pointer 50. On the short shaft 47 back of the gear 46 is carried a pinion 51, meshing with a gear carried by a short shaft or spindle 53, which also carries a small pinion 54 meshing with a registering gear wheel 55 forming a part of a hollow spindle 115 56. The pinions and gear wheels of the registering device being of such proportion that the gear 55 makes one revolution while the winding reel, to be described, is being filled. To the gear 55, is attached a dial 120 57 which is seated in the recess in the face of the gear 55 and is provided with a stem which is carried in the hollow spindle 56 of the gear 55.

In addition to the devices for registering the length of the fabric, there is provided an alarm which may be adjusted so as to automatically signal the operator when any desired amount of fabric may have been made, however, the capacity be- 130

ing that of the winding reel to be described. The alarm consists of a disk or cam 58 carried on the end of the spindle 56 opposite to the end which carries the gear 55 and the same is provided with a notch 59 in its periphery into which a pawl 60 drops when the notch 59 is brought co-incident with the pawl by the revolution of the disk. A lever 61 is pivotally connected to the pawl and by means of a spring 62, the lever is retained in such a position as to hold the pawl against the peripheral edge of the disk 58 and to the end of the lever 61 is attached a string 63 connected at its opposite end with any suitable alarm, so that when the pawl 60 drops into the notch of the disk 58, the movement of the lever will pull the cord 63 and strikes the alarm. The disk 58 may be adjusted in any suitable position relative to the gear 55 by the lock nut 64 which has a threaded connection with the end of the spindle of the gear 55; the adjustment being made according to the graduations which represent rods on the dial 56, compared with the pointer 63^a co-acting therewith.

The strand wires are fed into the machine from the winding drum 43 through guide tubes 64 carried by suitable brackets supported by the main frame. They are further directed by guides at various points throughout the machine, but these will be described in conjunction with other feeding and guiding devices.

35 The stay feeding mechanism for applying the sections of the stay to the strand wires, consists of a series of vibratory hoppers 65, the same being supported in rows above the path of the strand wires 30 and in the same are deposited short sections of stay in length to compare with the spaces between the strand wires to which they are fed. The succeeding sections of a stay, the adjacent ends of which are adapted to be 40 coiled around a coinciding strand are fed from hoppers alternately disposed in opposite rows. The bottoms of the hopper 65 are provided with slots or wire grooves 66 which communicate with vertically disposed 50 slots or grooves 67 and the slots 67 at the lower ends communicate with revolvably arranged disks 68 carried upon the shaft 28 and 70; the peripheral edge of the disks 68 being provided with the notches 71.

55 To insure a deposit of the stay sections into the slots 67 as was intimated the walls of the hoppers 65 are caused to be vibrated which keeps the stay sections in constant agitation and drops them one by one into 60 the slot 67, following each other successively as fast as they are removed from the slot 67 by means of the disks 68, the stay sections depositing themselves in the notches 71 of two or more disks and by the revolving of 65 said disks, they are fed farther into the ma-

chine. The arrangement of the hoppers is best seen in plan in Fig. 2 and in section in Figs. 11 and 12. The side walls of the hoppers 65 are provided with the lateral extended flanges 72 by means of which they are held in place by gibs 73 into which the flanges are dove-tailed and in such a manner as to adapt the walls of the hoppers to have longitudinal movement.

The mechanism for vibrating the hoppers 65 consists of the links 74 suitably connected with the sides of the hopper and with a bell crank lever 75 which is fulcrumed at 76 to a bracket 77, and to the bell crank lever is connected a rod 78 which at its lower end is connected with a strap 79 which is eccentrically connected with the power shaft 2. See Fig. 11 for the connection of the rod 78 with the bell crank lever and the hopper, and Figs. 3 and 4 for the connection of the rod 78 with the eccentrically connected strap 79.

The bottom of the hoppers is indicated as 80 disposed transversely across the machine and also serves as a support for various guides, brackets, etc. The slots 67 referred to which lead from the bottoms of the hopper, are made by the arrangement of guide plates 81 and 82 attached to and depending from the base of the hoppers and suitably spaced to provide the slot or groove 67.

Referring to the disks 68 which are so positioned as to receive the stay sections from the slots 67, the shafts to which they are attached are journaled in the guides 81 and are adapted to be intermittently and simultaneously revolved in opposite directions and upon coinciding ends of the shaft 28 and 70 are provided with the intermeshing gears 83 and 84; the shaft 28 extending out through the frame supports 1 and is driven through gearing from the shaft 21 in a manner and for a purpose to be described.

As the feeding disks 68 are revolved with the stay sections which are seated in the notches thereof, the said stay sections are carried forward by the revolution of the disks to a point in line with forming plates 85 suitably supported on the guides 82 and are made of harder material than the guides supporting them and are used to avoid excessive wear, it being more convenient to replace a forming plate than one of the guides. The disks are intermittently stopped and held stationary for a pre-determined period at which time, means is actuated for bending the opposite ends of the stay sections at right angles to their length. The guide plates 82 to which the forming plates are attached, have portions 86 which overlie a portion of the peripheral edges of the disks and serve to retain the stay sections on the disks during their movement under this portion of the guide plates and also to prevent

their becoming dislodged during the forming process.

The mode of forming or bending the stays, for purposes to be hereinafter described, is by means of a series of plungers indicated as 87, the same being arranged in pairs upon the outside guide plates 81 and 82, and are carried by angle bars 88 which extend transversely across the machine bed and upon 10 the opposite ends, support or have attached thereto the rack bars 89. The plungers are provided with the reduced stems 90 which project loosely through perforations or slotted openings in the upright portion of the 15 angle frames 88 and are held relative to longitudinal movement with the angle frames by means of cotter pins 91, see Fig. 13. The means for moving the rack bars and thereby moving the plungers which are 20 attached to the angle bars 88 which support the racks, is by means of the segmental gears 92 which are carried upon shafts 93 and adapted through the operation of the shafts 93 to intermittently project the plungers 25 87 and return them to their normal positions; the shafts have attached thereto the short levers 94 and the said levers are connected to the rods or bars 95 and 96 which at their outer free ends have yoke portions 30 97 carried by the shaft 21. The rods or bars 95 and 96 are each provided with rollers 98 adapted to be engaged by cams 99 which are carried by the shaft 21.

From an examination of Figs. 11 and 13, 35 it will be seen that by reason of the alternate disposition of the hoppers, the plungers are placed so that each alternate pair moves in opposite directions or toward each other, thus the opposing rack bars with 40 which the plungers are attached must be moved in opposite directions, and to accomplish this, the arrangement of the cams 99 on the shaft 21 and the disposition of the rollers on the rods or bars 95 and 96 must 45 be such that during the continued rotation of the shaft 21, the segmental gears 92 will be oscillated in opposite directions and thereby advance each alternate pair of plungers toward each other.

50 In the reciprocation of the plungers 87 the ends thereof will engage with the stay sections at or near the opposite ends and bend them forward against the forming plates 85. The disks which support the stay sections and the curved portions of the guides 82, serve to hold the body of the stay sections and prevent their bending, there being also provided, an intermediate series of disks 88 which will prevent the body of the stay sections from bending or buckling during the operation of bending the ends thereof. To insure that as the stay sections are bent, the ends thereof will be bent forward and lie against the forming plates and the guides, the plungers being arranged to be

reciprocated and at the same time have imparted to them, a circular or an oscillatory movement, and for this purpose, each of the plungers is provided with the inclined or cam faces 100 which in their movement, ride 70 against rollers 101 pivoted to the plates 102, see Figs. 11 and 13 and in Fig. 13 a pair of plungers are shown in dotted lines in their released position, the remainder of the figure showing the plungers projected and the 75 stay sections with their ends bent against the forming plates. In operating the segment gears and the racks the cams 99 operate against springs 103 which assist in returning the racks and plungers to their normal or released position. There are also provided springs 104 the opposite ends of which connect the shanks or extensions of a pair of plungers and are adapted to draw the shanks or extensions toward each other 80 as shown in dotted lines in Fig. 13 which separate the forward ends of the plungers and place them in the position to engage the extreme opposite ends of the stay sections to insure the proper bending thereof. 90

Referring to the plates 102 which have been described as extending transversely across the frames and to which the rollers 101 are attached; the same are supported by brackets 105 which in turn are supported by 95 extensions of the hopper gibs 73, and the brackets 105 are recessed as at 106, see Fig. 12, to receive the opposite ends of the plungers carrying frame 88 and serve as guides therefor. 100

To intermittently actuate the shaft 28 for imparting a corresponding movement to the feed disks 68 carried thereby and those upon the shaft 70, I provide on the outer end of the shaft 28, a wheel 107 which is intermittently revolved by means carried on the shaft 25 which is driven from the shaft 21. the last mentioned shaft receiving its power from the shaft 16 and it from the power shaft in the manner previously described. 110 In one of the faces of the gear 107 is provided a series of radial slots or grooves 108 extending from a point in the body of the gear to the peripheral edge thereof. On the shaft 25 is carried a short crank or 115 arm 109 and upon its outer free end is journaled a roller 110, and it is adapted that as the shaft 25 and the arm 109 is revolved, the roller 110 thereof will intermittently and successively engage with the slots or 120 grooves 108 of the gear 107 and causes the wheel 107 to advance the distance of the space between a slot which is sufficient to rotate the shafts 28 and 70 a sufficient distance to carry the feed disks forward to 125 place the stays which are seated in the notches thereof in a position to have their ends bent at right angles in the manner described. To lock the position of the shaft 28 and the gear 107 carried thereby while 130

the shaft 25 is making a partial rotation to bring the roller 110 to enter a succeeding slot of the gear, I provide the back of the gear with a series of semi-circular grooves 5 or pockets 111 which are struck on an arc of a circle whose center is the center of the shaft 25 and into which is adapted to be seated and revolved, a segment roller 112 which is attached to and revolved with the 10 shaft 25, the circular face of the roller operating in the pockets 111 simultaneous with the moving away of the roller 110 from the grooves 108. The notches 71 of the feeding disks 68 are so positioned relative to the 15 arrangement of the grooves 108 on the gear 107, that when the roller 110 leaves the gear 107 and the shaft 28 is caused to stop, the notches of the feeding disks 68 which are feeding forwardly a stay section will be in 20 line with the center of the forming plates 85 and the plungers 87, remaining in such a position a sufficient length of time for the process of bending or forming the stay sections, and as the shafts which carry the 25 feeding disks are again partially rotated, the feeding disks will carry the then bent stay beyond or below the end of the guide plates 82, when the stay section by gravity will drop on to reciprocally supported collecting fingers 113, which said fingers subsequently pass the stay sections to the strand wires around which the ends thereof are coiled.

The collecting fingers 113 are disposed beneath the feeding disks 68, there being a pair of such fingers to co-incide with the stay sections fed by the opposite and alternately disposed feeding hoppers, and the said fingers are rigidly attached to and carried 35 by transversely arranged bars 114, the opposite bars being operated through connections with shafts 115 and 116; the said shafts carrying cams 117 which operate against rollers 118 carried by yoke arms 119, 40 the yokes adapted to reciprocate across the axis of the shafts 115 and 116 and are connected to the bars 114 by blocks 120 through the stems 121, the yoke arms responding to the action of the cams by means of springs 45 122 attached to the opposite end of the bars 114 and to suitable frame parts, the springs shown attached to the bars 114 in Fig. 14. The collecting fingers 113 passed through guides 122^a which are suitably attached to the guides 81.

To advance the stay sections to their coiling position on the strand wires, I have provided the compression shoes 123 which are of suitable length and disposed vertically in 60 the machine adapted to act upon the formed ends of the stay sections and have broad enough faces to insure a proper contact with the formed ends of the stay sections. The forward movement of the compression shoes 65 will bring the formed ends of the stays

against blocks 124 which are attached to a swingably supported backing plate 125, the collecting fingers as will be seen in the drawings, pass through the compression shoes and have movement there through and simultaneously therewith. The compression shoes 123 and the blocks 124 serve as jaws between which the ends of the stay sections are firmly held, leaving a slight space between the body of the stay section and the 70 backing plate 125 for a purpose to be described. The compression shoes 123 are attached to rods 126 and the said rods are loosely carried through a carrier frame 127, nuts 128 engaging the ends of the rods 126 75 to connect them with the carrier frame, and 129 denotes coiled springs which are carried on the rods 126 and bear between the matching faces of the compression shoes and the carrier frame and serve as a cushion between the said shoes and the carrier. The compression shoes 123 and the carrier frame 127 through their connection therewith, are operated by cams 130, see Fig. 14, which are secured to the shafts 115 and 116 which 80 act upon the yoke stems 131, the latter passing through guides 132 supported by the previously described guides 80, the yokes being held to the action of the cams by springs 134 carried on the yoke rods 131 in 85 the manner shown in Fig. 14.

The backing plate 125 to which reference has been made, in its normal position, lies in the path of the formed ends of the stay sections as they are deposited on the collecting fingers 113 by means of the feeding disks 68, and to avoid an interference of the ends of the stay sections with the backing plate as the said stay sections are lowered, the backing plate 125 is caused to drop a sufficient distance to permit the formed ends of the stay sections to pass the backing plate, because of the fact, that as the stay sections are lowered, after their ends have been bent the ends will swing downwardly in an arc of a circle by reason of gravity from a horizontal to a vertical position, the body of the stay sections remaining in a horizontal position. Fig. 13 shows the stays just after forming and previous to 100 dropping and in Fig. 12 the formed ends of the stay sections are shown projecting downwardly with the backing plate in its normal position after being lowered and subsequently raised. The backing plate is 105 retained in its normal position by means of the supporting rods 133 which are connected with the opposite ends thereof and the said rods pass up through the base plate 80 and have a collar 134 attached to their 110 upper ends between which and the plate 80 are carried springs 135 which return and retain the backing plate 125 in its normal position after lowering. The means for 115 lowering the plate, consist of the levers 136 120

130

fulcrumed at 137 to brackets 138 supported from the lower face of the plates 102. The free ends of the levers 136 lie upon and are adapted to be intermittently raised by cams 139 which said cams are attached to the shaft 115. Thus it will be seen, that during the continued rotation of the shaft 115, the cams 139 will cause the oscillation of the levers 136 and cause the dropping of the 5 backing plate 125, the same being raised to its normal position through the action of the spring 135 as the irregular face of the cam moves away from beneath the lever 136. The manner of driving the shaft 115 is through a sprocket chain connection 140 with the previously described shaft 21 which connects with a sprocket 141 thereon and with a sprocket 142 on the shaft 115, see Figs. 11 and 14; and the shaft 116 is 10 driven in unison with the shaft 115 by means of a chain 143 connecting a sprocket 144 on shaft 116 with a sprocket 145 on the shaft 115. The shafts 115 and 116 are journaled in bearings 146 which are supported 15 on the lower face of the plates 102, see Fig. 11.

In the further delivery of the stay sections as they are advanced to the strand wires around which they are coiled, I employ 20 a series of delivering forks 147 which are adapted to have vertical movement and move the stay sections from between the compression shoes 123 and the blocks 124. The lower portion of the delivering forks 30 have the bifurcated extensions 148 which lie adjacent to the backing plate 125, somewhat in the manner as shown in Fig. 12. To the faces of the extensions 148 which move adjacent to the stay sections, is attached 35 the flat springs 149, see Fig. 18; the upper ends only thereof being connected, the lower ends curved outwardly as shown and at a point about the center of the spring there is provided a stop pin 150 secured to 40 the extension of the fork and projecting loosely through an opening in the spring. When the delivery forks are in their extreme raised or normal position, the springs 150 are disposed slightly above the stay 45 sections, and as the forks are lowered, by means to be described, the stay section is wedged between the fork extensions and the springs. The forks are extended until the stay sections abut with the pins 150 in which 50 position they are wedged between the extensions of the forks and the springs, the latter holding them against such extensions, and the means for actuating the forks is so arranged that as soon as the sections 55 are caught up by the said forks, the latter are slightly raised to permit the compression shoes and the collecting finger to recede, the raising of the forks relieving 60 any pressure of the sections against the compression shoes and the collecting fingers 65

and as soon as the said collecting fingers and compression shoes recede, the delivering forks are again continued in their downward movement to deposit the stay sections on the strand wires at a point between a 70 suitable knotter or twister plate to be described. The shanks or upper portions of the delivering forks 147 extend up through the plate 80 and their extreme upper ends are attached to a transverse bar, the opposite ends of the bar being provided with rollers 152 which operate in vertical guides 153 and also in slots 154 of levers 155. The guides 153 are supported by the gibs 73; and on one end of the gib 73 is secured a 80 bracket or arm 156 to which the lever 155 is pivoted at 157, and to the lower end of the lever 155 is attached a spring 158 which at its opposite end is suitably secured to some frame part and draws the lever in an upward position and the delivering forks also, the said spring yielding to the actions of a cam 159 secured to the shaft 21 which operates at pre-determined intervals to lower the delivering forks, by engagement with a 90 roller 160 attached to the lever, see Fig. 11. The irregular portions of the cams 159 are such that during the lowering of the forks at the time when they receive the stay sections, will cause the said forks to raise 95 slightly and be again lowered for the purposes above stated.

As the delivering forks 147 are raised from their lower position, the stay sections are drawn from beneath spring plates 149 100 and the extension of said forks are retained in the position in which they are placed upon the lowering of the forks, as the latter are raised to their upper normal position, which is accomplished by means of the reciprocally 105 arranged gripping fingers 161, see Figs. 19 and 20 which are adapted to be advanced and the forward ends thereof carried over the body of the stay sections and hold them in their place on the strand wires while 110 the forks which lower them to this position, are being raised. These gripping fingers operate through a suitable housing 162 which serves as a guide for the fingers and at 163 the fingers are off-set or bent out of 115 line in order that a bar 164 to which the rear ends are attached and which serves as a carrier therefor, may lie out of the path of the strand wires. The opposite ends of the carrier bar 164 are pivotally attached to 120 levers 165 which are fulcrumed at 166 to a suitable bracket 167 in the bed frame. The lower ends of the levers 165 have a pivotal connection with a yoke rod 168, the yoke of which is movable across the axis of the shaft 16, and movement is imparted to the yoke rod 168 by means of a cam 169 carried by the shaft 16 which operates against a roller 170 carried by the yoke rod for the purpose of reciprocating said rod and 130

through the lever connection with the carrier bar 164 reciprocate and extend the gripping fingers 161; the gripping fingers being extended as shown in Figs. 19 and 20.

- 6 There is provided springs 171 attached to a suitable frame part and to the upper end of the lever 165 for yieldingly holding the roller 170 against the cam 169.

The knotted plates or coiling disks which

- 10 coil the formed ends of the stay sections around the strand wires, are best seen in Figs. 21, 22, 23, 24, 25, 26 and 27. In the feeding of the strand wires they are carried through the center of the knotted plates or

- 15 coiling disks, and the stay wires as they are lowered by the delivering forks, they will be deposited with their bent portions overhanging adjacent strand wires somewhat as shown in Fig. 24.

- 20 The coiling disks for coiling the ends of the stay sections around the intermediate strand wires are constructed slightly different from the disks which coil the outer end of the upper and lower stay sections

- 25 around the selvage wires. The coiling disks for the stays of the intermediate strand wires, are arranged in pairs and will be referred to as knotted plates 172 and 173 which are brought adjacent to each other

- 30 and interlock the co-inciding ends of the opposite stay sections and coil their ends in opposite directions around a strand wire.

The disks which co-incide with the selvage strands, will be indicated as 174 and

- 35 175 and will be referred to as a coiling and a seating plate; the disk 174 adapted to have seated in a groove therein through the action of the disk 175 one end of a stay section which will be coiled around the selvage

- 40 strand, there being only one section of a stay, there is no need of a coiling disk such as employed with the intermediate strand wires, there being no necessity for interlocking the end of the stay section. See Fig.

- 45 33 in which a view of the fabric is shown and the form and manner in which the stay sections are coiled around the intermediate and selvage strand wires. In Figs. 24 to 27, is shown the manner of carrying the

- 50 stay sections in the twister and knotted plates and the manner in which they are coiled around the strand wires. For convenience, the selvage wires will be indicated as A, the intermediate strand wires as B, the

- 55 stay sections as C, and the formed ends D which are coiled around the intermediate strand or selvage wires.

- The selvage twisting plates 174 are provided with a lug 176, which, during the

- 60 revolution of the twister plates engages the ends D of the stay sections and directs them around the selvage wires A. The face of the lug 176 is provided with a groove 177 adapted to receive the formed end of the

- 65 stay section and hold it steadily during the

operation of coiling the same around the selvage wire. The seating plate 175 is provided with a lug 178 which is adapted to seat the formed end D in its place on the twisting plate 174. By means to be de- 70

scribed, it will be shown that the twister plate is adapted to be revolved, while the seating plate is not, and when the two plates are brought with their matching faces adjacent or against the stay section, 75 the lug 178 on plate 175 will hold the formed end D of the stay section in front of the acting faces of the driving lug 176 and seat the end D of the stay section against the plate 174 in the path of the groove 177 of 80 the lug 176, so that as the plate 174 is revolved, the end D of the stay section will be seated in the said groove or engaged thereby and be carried forward by the lug and around the selvage wire A, after which re- 85 sisting pressure of the wire holds it firmly in the groove 177.

The stationary position of the plates 174 and 175 is such that only a slight movement is needed to cause the groove 177 in the lug 90 176 to engage the end of the stay section. To prevent the driving lug 176 from interfering with the body of the stay section C during the revolution of the twisting plate, there is provided a seat, tapered or beveled 95 face 179 on the plate 174, as shown in Figs. 22 and 24, against which the formed end of the stay section C is forced by the lug 178, the groove 177 in the lug 176 corresponding also to the angle of the bevel face 179 and 100 conforms to the pitch at the end of the stay sections which are wound around the strand wires. The lugs 176 and 178 have inclined portions 180 and 181, so that the combined action causes them to separate sufficiently 105 at the point where the driving lug 176 passes the body of the stay section, which is held back against the opposite plate by the angle in which it is carried in the groove in the lug 176. 110

The knotted plates 172 and 173 operate in conjunction with each other in a manner similar to the twisting and seating plates 174 and 175. As previously referred to, Figs. 25, 26 and 27 represent a pair of these 115 knotted plates for the intermediate wires and show them in various stages of operation, the resulting knot and coil of the co-inciding stay sections requiring a proper relation of the same to each other and the 120 knotted plates when the former are deposited on the strand wires. In the drawings, the plates are separated to afford a better view of the various steps in the process of forming the knot and coiling the 125 stay sections by the knotted plates. Each of the knotted plates are provided with means for seating an adjacent stay section in its opposite plate and each pair of knotted plates are identical in so far as the 130

process of forming the knot is concerned, but one series of the knotter plates are constructed so as to be removed out of line of the strand wires after a stay has been 5 formed, this is also true of the seating plate 175 which co-acts with the twister 174. The knotter plates are provided with a seating lug 182 and also with the driving lug 183, being similar to the driving lug 180 of the 10 twisting plates 174 and having the grooved wire receiving faces 184. The lugs 182 and 183 on the co-acting knotter plates are so disposed that when the two faces are brought together, the lug 182 of one plate is 15 opposite the lug 183 of its co-acting plate and the lugs 182 are interlapped at 185 which insures the control of the opposite ends of the co-inciding stay sections and assist in forcing the ends of the stay sections 20 in the grooves 184 of their corresponding lugs 183. Each of the lugs 182 and 183 are provided with the tapered or beveled portions 186 and 187 which together with the grooves 184 are inclined to conform with 25 the pitch at which the stay sections are coiled around the strand wire, and act substantially the same as the tapered faces of the plates 174 and 175. In Fig. 24 the relation of the lugs on the plates 172 and 173 30 are plainly shown and it is readily apparent, the manner in which the plate 172 received the end of the stay section which lies adjacent to the face of the plate 173, when the two plates are brought together, which is 35 also true of the plate 173 which will receive the stay section lying adjacent to the plate 172, in such a manner that as the two plates are revolved in opposite directions, they will inter-lock around the strand wire 40 B and be coiled in opposite directions thereon, and as fully illustrated in Figs. 25, 26 and 27.

The knotter plates, and the twisting plates are secured to hub extensions 188 of reciprocally disposed driving gears 189 which have the further extended hub portions 190 provided with the annular grooves 191; the hubs of the gears forming bearings therefor and also serve as journals for the knotter 50 and twister plates, the hubs of the gears having bearings in the housings 162 and 192 and are of sufficient length to permit of their being reciprocated as above suggested. The seating plates 175 which are used in conjunction with the selvage wires, are secured 55 to plungers, 193 and are provided with annular grooves, adapted to have the same longitudinal movement as the knotter and twister plates, but they do not revolve. For 60 the set of gears 189, carried in the housing 162, there is a yoke arm 195 having suitable connection with grooves 191 arranged in the hubs thereof. The yokes 195 have connected therewith, short stems 196 which 65 pass loosely through a carrier bar 197 and

the outer ends of the stems are provided with a suitable washer and cotter pin to prevent the stems 196 from becoming dislodged and around the stems is coiled the cushion springs 198 which are seated against 70 the yokes 195 and the carrier 197. The carrier bar 197 is connected at its opposite ends to rods 199 which slide in guides 200, the said guide suitably supported in the main frame. The forward ends of the rods 199 75 are guided in their movement by being passed through extensions of the housing 162 and are connected by a knuckle joint 201 with rods 202 which extend forwardly in the bed frame and are suitably connected at the upper end with levers 203 which are fulcrumed at their lower ends at 204, see Fig. 20. The levers 203, are adapted to be oscillated through the action of disks 205 on the driving shaft 10, the same carrying 80 rollers, adapted during the revolution of the disks 205, to engage with portions of the lever and cause the same to be oscillated for the purpose of drawing the carrier bar 197 forward through its connection with the 90 rod 202 and thereby move the twister plates and the knotter forward a short distance.

The disks 205 in their movement, act against resistance springs 206 which are carried on the rods 199 and bear against a 95 collar on said rod and the housing 162. It is to be understood that through action of the lever 203 and the connection with the twister and knotter plates, that the movement of said knotter plates also causes a 100 simultaneous shifting of the gears with which they are connected and that the means for driving the gears for actuating the twisters and knotter plates, is such that the gears are capable of being moved while remaining in connection with their power devices. 105

For the set of gears 189 carried in the housing 192 there is provided a yoke arm 206^a having suitable connection with the grooves 191 arranged in the hubs thereof. 110 The yoke arms 206^a are integral parts of levers which are fulcrumed at 207 to brackets 208, and the said brackets are fixedly connected with a vertically reciprocal cross head 209. To a point approximately the center of each lever, is pivoted a stem 210 which slides freely in and are carried by the channel bar 211 and locked to the channel bar by suitable washers and cotters. The pressure exerted by 115 the channel bar is imparted to the levers 206 through cushion springs 212 carried upon the stems 210 as shown in Fig. 20. For a reason which will be made obvious later, the channel bar 211 is connected to a yoke rod 213 by a knuckle joint 214. This yoke rod passes through a guide 215 supported by a suitable frame, the yoke of the rod indicated as 216 and carries a roller 217 which is adapted to be intermittently actuated by 120 125 130

a cam 218 carried on the shaft 10 for oscillating the levers 206 through the connections described at predetermined intervals. The cam 218 imparts its motion to the yoke 5 rod against the resistance of a spring 219 carried by the yoke rod and bearing between a collar thereon and the guide 215.

The gears 189 which are carried in the housing 162 coact with pinions 220 with 10 which they have a slidable relation; the pinions 220 carried on one end of shafts 221, journaled one end in the housing 162 and the other end in suitable bearings 222, and on their outer end, carry pinions 223 which 15 intermesh with beveled gears 224 carried by a transverse shaft 225. The shaft 225 is adapted to be actuated intermittently through the connection of a pinion 226 carried by the said shaft and a segmental gear 20 227 carried by the secondary driving shaft 16.

The pinions for driving the gears 189 in the housing 192 are also referred to as 220 and similar to those previously referred 25 to, and the gears 189 which mesh therewith also have a slidable connection. The shafts supporting the said pinions, will be indicated as 228 which have journaled bearing in the housing 194 and also in suitable 30 boxing 220. Motion is imparted to the said shaft in a manner similar to the shaft 225 by the provision of pinions 230 which intermesh with bevel gears 231 carried by a transverse shaft 232, on the outer end of which 35 is carried a pinion 233 adapted to intermesh with a segmental gear 234 carried by the driving shaft 10. The shaft 228 is made in two sections which are connected by a suitable flexible coupling 235.

40 To compensate for the wear of the end teeth of the segment gears 227 and 234 indicated as 236, I have made the same adjustable radially by means of a screw 237, the same being locked to the body of the gear 45 by a screw 238 which passes through a longitudinal slot in the body of the tooth.

It is of course understood, that as the strand wires are advanced through the machine they must necessarily pass through 50 the gears 189 and the twister and knotter plates attached to said gears and that the stay sections are locked and coiled on the strand wires between the matching faces of the twister and knotter plates as hereinbefore specified; now in order that the strand and selvage wires may be advanced through the machine for the purpose of successively introducing a series of stays, all 55 of the twisting and knotting mechanism lying on the side of the stay wires toward which they are advanced, must be removed from the path of the stays. For this purpose, all of these twisters and knotter plates together with the gears which drive 60 them, are slotted from their centers out-

ward, as shown in Figs. 19 to 27. The slots of the twisters, knotters and gears are so positioned, that when the gears, twisters and knotters are in their stationary position, the slots are turned upward, and the 70 the bearings in which they are journaled, are correspondingly slotted to permit of their complete removal downward from the strand wires. The slots of the seating plates, the twisters and knotters are indicated as 75 239, and to provide against any inaccuracy, these slots are tapered radially, as shown in Figs. 24-27.

The housing referred to as 194 is supported by the cross head 209; the cross head 209 is vertically movable in guides 240 secured to the bed frame, and attached to the guides or extensions thereof, is a roller indicated as 241 which is adapted to ride upon cams 242 carried by a cross shaft 243; and secured to the shaft 243, is a crank arm 245 to which is pivotally connected, a yoke rod 246, the yoke of which is carried upon and slidably across the axis of the shaft 10. The said yoke rod has attached thereto, a roller 247 which is acted upon by a cam 248 attached to the shaft 10 for the purpose of imparting reciprocation to the rod 246 which through its connection with the shaft 243 will rotate the same and facilitate in the lowering 90 and raising of the housing 194 together with the slotted twister and knotter plates. The flexible coupling in the shaft 228 and the knuckle joint between the rods 210 and 213 permitting of such vertical movement of the 100 said twister and knotter plates.

I have provided in connection with the apparatus, a crimping device, for crimping the strand wires at points between the coils of the stay sections therewith, the same being shown more clearly in Figs. 28 and 29. The strand wires are passed between plungers 249 and a bed plate 250, which by suitable means prior to the operation, are separated sufficiently for the free passage of the strand wires which at this time are equipped with the stays, the strand wires being guided by the plungers and the bed plate by means of a pair of rollers 251 journaled in a vertically adjustable support 252. The plungers 249 are carried in a beam 253 and are adjusted therein by means of the screws 254 and then locked in their adjusted positions by the screws 255. To the opposite ends of the beam 253 is secured a plate 256 provided with flanges 257 which ride between rollers 258, the said rollers being secured to a supporting plate 259 suitably attached to the bed frame. The bed plate 250 has its ends mounted on brackets 260 which are 110 slidably supported on rods 261, the said rods carried by a frame 262 which are supported on a cross head 263, the same adapted to have vertical movement in guides 264, through the connection 264 by means of a 120 130

bracket 265 which is attached to the cross head 263 and carries the rollers 266. 267 indicates a transverse shaft journaled in the plates 259 and carries the cams 268 on which 5 the rollers 266 ride, and by means of said cams, the cross head 263, is adapted to be raised and lowered. To the shaft 267 is attached the crank arm 269 which has pivotally connected therewith, a yoke rod 270 10 which extends forward and has the yoke portion thereof carried by and reciprocal across the axis of the shaft 10, the said shaft carrying a cam 271, see Fig. 19, which engages with a roller 272 on the rod 270 for 15 intermittently and at predetermined intervals oscillating a rod 270.

As previously described during the placing of the stay sections on the strand wires, the latter remain at rest at which time the 20 operation of crimping is also performed. The crimp in the strand wires is placed at a point midway between the stay sections and to insure this, provision is made against any slight inaccuracy in the spacing of the 25 stay which inaccuracy would be multiplied due to the number of stay sections between the point where the crimping is done and the point where the stay sections are applied and spaced. For the purpose of properly 30 locating the crimp, the plunger 249 and the plate 250 are adjustable in their relation to the stays. To keep the plungers and plate 250 in line with each other, they are connected by the rods 273 which are secured at 35 their lower ends in the bracket 260 and slide vertically in the guiding brackets 274 which are secured to the plates 275. The adjustment is accomplished by a hand lever 276, see Fig. 3, which may be held in any position by a friction shoe bearing against a quadrant 277 by means of a spring, the same being controlled by the latch handle 278. The lever 276 operates a shaft 279 to which 40 is secured arms 280, see Fig. 4, which are connected by rods 281 to the plates 275. The shaft 279 is suitably journaled in bearings supported by the bed frame and serves as a support for the quadrant, one end of which is attached to the bed frame.

50 The completed fabric is wound upon a reel 282, journaled on the shaft 283 which has bearing in the main bed frame; the complete plan of the machine in Fig. 2 shows the reel, the individual strand wires and the completed fabric as the same is fed and wound upon the reel. On one end of the shaft 283 is carried a pinion 284 which meshes with the gear 285 carried by a short shaft 286 supported in bearings on one of 55 the frames 1. It is adapted to drive the reel intermittently thus allowing the strand wires to be at rest while the stays are being applied; for this purpose, a ratchet wheel 287 is attached to the shaft 286. The 60 ratchet wheel is driven by pawls 288 held

against the same by gravity and are pivoted to a plate 289 secured to the upright 290 which is attached to oscillate upon the shaft 286.

291 indicate bars which act as pawls on 70 the ratchet wheel 287 and are connected to the arms 290 by the guide lugs 292, the opposite ends of which are joined by the strap 293 and the plate 289. These pawls slide freely between the guides and rest against 75 the face of the ratchet by gravity. There is also provided pawls 294, which engage with the teeth of the ratchet wheel 287 and prevents the same from revolving backward. It is seen therefore, the difference in the 80 length of the two pawls 294 and also the two pawls 288 is equal to half the pitch of the teeth of the ratchet wheel 287 thereby causing one or the other of each pair of pawls to engage the ratchet at intervals equal to half 85 the pitch of the ratchet teeth. The arm 290 is oscillated by attaching thereto, a rod or bar 295 which is pivoted to a compensated block 296 connected in the manner shown in Fig. 32 to the arm 290; the opposite end of 90 the bar or rod 295 is adjustably connected with a lever 297, see Fig. 1, to facilitate in getting a longer or shorter stroke to obtain a variety of space between the stays; the lever 297 being fulcrumed at its lower end to 95 a bracket 298 to the main frame. The lever 297 is oscillated by attaching thereto, a yoke arm 298 slidably in a guide 299 secured to the main frame.

300 is a crank arm secured to the driving 100 shaft 10, and carries a roller 301 adapted in the rotation of the shaft 10 to alternately engage the oppositely disposed notches 302 in the yoke arm for the purpose of alternately reciprocating the same 105 thereby oscillating the lever 297 and reciprocating the bar 295.

The compensating block 296 is to compensate for the increase in the motion of the reel, due to the increase in the roll 110 of fabric being wound thereon. In the same proportion as the roll of fabric increases in diameter, the block 296 travels away from the center of the shaft 286. The block is moved by a screw 303 journaled at the 115 top in a cross head 304 of the arm 290 and at its lower end in the hub of the said arm, and on the lower end is secured a friction roller 305 which engages with the face of a disk 306 attached to or forming a part 120 of the ratchet wheel 287. The friction roller is held in contact with the disk of the ratchet by pressure exerted against the hub of the arm 290 by a spring 307 carried on the shaft 286, see Fig. 30. The 125 block 296 is properly adjusted on the screw 303 for producing the proper throw of the pawls 288 at the beginning of the winding of the fabric on the reel, by first releasing the pressure of the friction roller 305 and 130

- turning the screw by means of a crank arm or wrench secured to the upper end of the screw when the same may be turned and the block 296 lowered to its proper position.
- 5 When the roller 305 occupies its proper position the advance of the disk 306 with the ratchet wheel causes the roller to turn the screw and advance the block in the same proportion as the fabric increases in diameter on the reel, thereby advancing the line wires or the fabric in equal steps regardless of the contents of the reel.
- The complete operation of feeding strand wires through the machine, feeding and coiling stay sections thereto and thereon and wrapping the finished fabric or winding the same upon the reel, may be briefly described as follows:—The machine is threaded with strand wires as shown in Figs. 1, 2, 3 and 4; the wires entering the machine through the tension devices, traveling once around the equalizing drums through the guide tubes 64, thence through the knotting mechanism and between the guide rolls, and 25 the crimping mechanism and anchored to the winding reel. The vibratory hoppers are filled with a supply of short sections of stay which have been previously cut to the proper lengths, and by means of the lever 6, the clutch mechanism is set for the purposes of imparting power to the driving shaft 2 and from the same to the secondary shafts, and other devices as previously described.
- 30 35 The reciprocation of the hoppers cause the stay sections to be deposited in the slots 67 from whence they are taken up successively and intermittently by means of the feeding disks 68 and carried to the forming plates 85; the forming plungers 87 are then reciprocated and the ends of the stay sections bent into proper form. The plungers are then released while the collecting fingers 113 advance to receive the 40 stay sections which are deposited thereon by the feeding disks after the action of forming, the backing plate 125 being dropped to allow the ends of the stay sections to clear as they are received by the 45 collecting fingers, when the backing plate is again raised to its normal position. The compression shoes 123 are advanced, slide the stay sections along the collecting fingers and hold them firmly, when the delivering 50 forks are caused to descend to gain control of the stay sections, when the compression shoes are released and the delivering forks are caused to further descend and deposit the stay sections on the selvage and 55 intermediate wires A and B, when the gripping fingers 161 are advanced and lie over the stay sections to prevent their rising when the delivering forks are raised to their normal position. The knotter, twister and 60 seating plates are at this time compressed 65

against the stay sections, when the gripping fingers 161 are released and the knotter, and twister plates set in motion. During the first revolution of the knotting and twisting plates, they are separated by their lugs after which they recede in conformity with the pitch of the twist against the pressure of the cushion springs described, by being crowded back by the body of the stay sections as the same are wound or coiled upon the strand wire. The cams 218 and the lever 203 are so shaped that after the first revolution of the said twisting and knotter plates, they release the pressure of the plates. The device for actuating the plates are such that an extra revolution of the twister and knotter plates is made for the purpose of tightening down the ends of the stay sections, or impinging them against the body of the strand wires, after which they stop in a position, which is such, that only a slight movement in their rotation is sufficient to cause the wire receiving grooves in the driving lugs of the twister and knotter sections to engage the ends of the succeeding stay sections. The knotter and twister plates are then removed from the stay sections, and the series of knotter and twister plates together with their supporting and operating device on the side of the stay toward which it advances, is lowered from the path to permit the strand wires to be advanced. The winding reel advances the strand wires to permit the placing of each successive stay and also advances the strand wires to their proper position in the crimping mechanism; the knotter and twister mechanism again rising to their normal position while the strand wires are at rest; the operation of crimping is performed and the product thus completed is conveyed to and wound upon the reel.

It is obvious that various details may be made and modifications resorted to in the construction of the various parts of the machine with affecting the principal and scope of the invention herein and I do not wish to be confined to the various details of parts as herein shown, where it is possible to substitute equivalents or reduce the number of parts without affecting the operation of advancing both the strand and stay wires to coil the latter around the strand wires.

Having thus fully described my invention what I claim and desire to secure by Letters Patent of the United States, is:—

1. In a fence machine, strand wire feeding mechanism comprising tension devices, and an equalizing drum; stay feeding mechanism consisting of vibratory hoppers and feeding disks, and means for coiling the stay around the strand wires, substantially as specified.
2. In a fence machine, the combination of

feeding mechanism, mechanism for depositing short sections of stays across the strand wires with the ends thereof turned downwardly, and a series of coiler heads adapted 5 to engage the down turned ends of each stay section and coil the same around the strand wires.

57. In a wire fence machine, strand wire feeding mechanism, mechanism for depositing short sections of stays across the strand wires with the ends thereof turned downwardly, and a series of oppositely disposed and reciprocal coiler heads adapted to be moved to engagement with said down turned 15 ends of said stay sections and interlock and coil the same about a coinciding strand.

58. In a wire fence machine, the combination of two series of twistlers, each series operating for each twister of the series to engage the down turned end of a section of a 20 divided vertical or stay wire and coil such end around a main or strand wire, with the twistlers of one series having a rising and falling movement, and each twister of the 25 rising and falling series having a slot for the passage of the main or strand wires for allowing the advance of the wire fence when

the twistlers of the rising and falling series are dropped below the plane of movement of the fence. 30

59. In a wire fence machine, the combination of two series of twistlers, each series operating for each twister of the series to engage the down turned end of a section of a divided vertical or stay wire and coil such 35 end around a main or strand wire, with the twistlers of one series having a rising and falling movement, and each twister of the rising and falling series having a slot for the passage of the main or strand-wires for 40 allowing the advance of the wire fence when the twistlers of the rising and falling series are dropped below the plane of movement of the fence, and means for raising and lowering the twistlers of the rising and falling 45 series.

In testimony whereof I affix my signature, in presence of witnesses.

revoluble feeders adapted to receive the stay sections from the receptacles, means for bending the ends of the stay sections, gripping devices for receiving the formed stay sections, and vertical reciprocally disposed forks provided with means for engaging the stay sections while retained in the gripping devices, means for moving the gripping devices, and means for descending the forks 10 for the purpose of carrying the stay sections to the strand wires, simultaneous with the moving away of the gripping devices, substantially as specified.

32. In a wire fence machine, the combination with devices for feeding short sections of a stay, forming plates, and a series of reciprocal plungers adapted to act upon and bend the ends of the stay sections, the said plungers as they are reciprocated being oscillated for the purpose of following the bent portions of the stays, substantially as specified.

33. In a wire fence machine, the combination of a series of vibratory hoppers, disposed alternately in opposite rows, a pair of driving shafts disposed beneath and across the hoppers of each row, revoluble feeders carried by the said shafts, and beneath the hoppers and a series of reciprocal and oscillatory plungers for acting upon the ends of the stay sections to bend the same, means for actuating the plungers, and means for oscillating the same, as they are reciprocated, substantially as specified.

35. 34. In a wire fence machine, the combination with stay containing receptacles, feeders co-acting therewith, reciprocally carried plungers for acting upon the stay sections while retained in the feeders, the said plungers having cam faces engaged by rollers for the purpose of causing them to travel in a sinuous line when they are reciprocated, substantially as specified.

35. In a wire fence machine, the combination of a series of coiling plates, a frame for supporting said coiling plates, driving means for the coiler journaled in the frame, means for moving the coilers longitudinally, and means operating at pre-determined intervals for lowering and raising the frame which carries the coilers, substantially as specified.

36. In a wire fence machine, the combination of a frame adapted to be reciprocated in a vertical plane, a housing attached to the frame, gears journaled in the housing, coiling plates attached to the gears, means for reciprocating the frame, and means for imparting longitudinal movement to the gears, substantially as specified.

37. In a wire fence machine, the combination with a bed frame, of a row of gears adapted for rotation and for reciprocation in their bearings, coilers attached to the

gears; a housing supported in the bed frame 65 and adapted to be reciprocated in a vertical plane, a second series of gears journaled in the housing and adapted for rotary and longitudinal movement, means for rotating the gears, and means for raising and lowering 70 the housing, substantially as specified.

38. In a wire fence machine, the combination of two rows of oppositely placed gears, co-acting coiling plates supported by the opposite gears, a series of shafts carrying gears intermeshing with the gears carrying the coilers, means for driving the said shafts, means for longitudinally reciprocating the gears to bring the opposite coilers adjacent, and means for projecting one series of coiling gears in a vertical plane, substantially as specified.

39. In a wire fence machine, the combination with stay carrying receptacles, of a series of intermittent rotary feeders, and 85 a series of forks adapted to be reciprocated in a vertical plane and having bifurcated extensions provided with spring gripping members, all arranged substantially in the manner and for the purpose specified. 90

40. In a wire fence machine, the combination with revolubly disposed stay feeding devices, of reciprocally arranged gripping fingers for receiving the stays, an oscillating backing bar, and yieldingly arranged 95 compression blocks coöperating with the backing bar, substantially in the manner and for the purpose specified.

41. In a wire fence machine, the combination with stay feeding devices, means for forming the ends of the stays, a backing bar, means for lowering the stays, compression shoes coöperating with the backing bar for laterally moving said stays, and means for lowering the backing bar 100 at pre-determined intervals to permit the formed ends of the stays to drop in a vertical plane, substantially as specified. 105

42. In a wire fence machine, the combination of stay carrying receptacles, revoluble feeders for receiving the stays from the receptacles, longitudinally movable plungers adapted to act on the ends of the stays to bend the same, a backing plate longitudinally movable, means for receiving the formed stays and 110 compressing them against the backing plate, and means for moving the backing plate out of the path of the stays to permit the formed ends thereof to drop in a vertical plane, coiling devices and means for carrying the 115 formed stays to the coiling devices, substantially as specified. 120

43. In a wire fence machine, the combination of a tension feed for strand wires, consisting of a grooved roller journaled in a 125 stationary base, a second grooved roller co-acting with the first mentioned roller and journaled in a swinging frame, and means

for yieldingly holding the said rollers in frictional engagement, substantially as specified.

44. In a wire fence machine, the combination of a tension feed for strand wires, consisting of a grooved roller journaled in a stationary base, a second grooved roller overlying and co-acting with the first mentioned roller and journaled in a swinging frame, 10 means for yieldingly holding the said rollers in frictional engagement, and a yieldingly carried brake shoe for engaging the roller in the fixed frame, substantially as specified.

45. In a wire fence machine, the combination with a driving shaft, of a pair of feeder shafts carrying disks adapted to receive and convey stay wires, intermeshing gears on the said feeder shafts, and intermittently actuated means connected with the driving 20 shaft adapted to impart motion to the feeder shafts, substantially as specified.

46. In a wire fence machine, the combination of a pair of feeder shafts, carrying intermeshing gears, a series of wire stay conveying members carried on said shafts, a driving shaft, a short shaft and connections between the short shaft and the driving shaft, and intermittently actuated gearing carried by one of the feeder shafts and the 30 short shaft, to facilitate in imparting an intermittent motion from the driving shaft to the feeder shafts, substantially as specified.

47. In a wire fence machine, crimping mechanism comprising a series of vertically 35 and laterally adjustable bars, an adjustable crimping plate co-acting with the said bars, and means for moving the said crimping plate toward and from the adjacent bars, substantially as specified.

48. In a device of the class described, the combination of stay and strand wire connecting devices, comprising two oppositely placed wire connecting members, and longitudinally movable supports on which said 45 wire connecting members are mounted.

49. In a device of the class described, the combination of stay and strand wire connecting devices, comprising two oppositely placed wire connecting members, longitudinally movable supports on which said wire connecting members are mounted, and means for raising and lowering one of said supports.

50. In a device of the class described, the combination of stay and strand wire connecting devices, comprising a plurality of oppositely placed wire connecting members, longitudinally movable supports on which said wire connecting members are mounted, 55 and one of said supports capable of being moved vertically, means for moving the supports toward and from each other, and means for raising and lowering the vertically movable support.

51. In a device of the class described, the

combination of stay and strand wire connecting devices, comprising a plurality of oppositely placed wire connecting members, supports for said connecting members adapted to be automatically moved toward and from each other, and means for so moving the said supports. 70

52. In a device of the class described, the combination of a series of coiling members disposed in rows opposite to each other and arranged for the passage therethrough of strand wire, means for placing short sections of stays with their opposite ends across adjacent strands, and means for operating said coiling members to cause the same to lock 80 the ends of adjacent stay sections about each other and coil the same on the strands. 75

53. In a device of the class described the combination of a series of coiling members disposed in rows opposite to each other and arranged for the passage therethrough of strand wires, means for placing short sections of stays with their opposite ends across adjacent strands, means for advancing the opposed coiling members toward each other 90 to lock the ends of adjacent stay sections across each other, and means for operating said coiling members to coil the ends of adjacent stay sections in opposite directions along the strands. 85

54. In a wire fence machine, a pair of parallel frame supports normally spaced apart, a plurality of coiler heads mounted in the said supports and oppositely disposed to each other, means for feeding strand-wires through each pair of oppositely disposed coiler heads, means for depositing short sections of stays with their ends across adjacent strands, means for simultaneously reciprocating the coiler supports toward each other, means for operating said coiler heads for interlocking the ends of adjacent stay sections and coiling them about a coinciding strand, and means for moving said coiler supports apart from each other. 95

55. In a wire fence machine, a pair of parallel frame supports normally spaced apart, a plurality of coiler heads mounted in the said supports and oppositely disposed to each other, means for feeding strand wires through each of the oppositely disposed intermediate coiler heads and selvage wires through the outside of said coiler heads, superposed stay feeding devices for depositing stay sections across said strand wires, 110 means for simultaneously reciprocating the coiler supports toward each other, means for operating the coiler heads to interlock and coil the adjacent ends of the stay sections around corresponding strand wires and for 115 coiling the outer ends of the outside sections about the selvage wires, and means for moving said coiler supports apart from each other. 120

56. In a wire fence machine, strand wire 130

Correction in Letters Patent No. 1,025,858.

It is hereby certified that in Letters Patent No. 1,025,858, granted May 7, 1912, upon the application of Edmund E. Brown, of Bloomington, Illinois, for an improvement in "Wire-Fence Machines," an error appears in the printed specification requiring correction as follows: Page 12, line 111, for the word "with" read *without*; and that the said Letters Patent should be read with this correction therein that the same may conform to the record of the case in the Patent Office.

Signed and sealed this 11th day of June, A. D., 1912.

[SEAL.]

C. C. BILLINGS,

Acting Commissioner of Patents.
